BINDER

Filed Sept. 23, 1927

UNITED STATES PATENT OFFICE.

FRED J. KLINE, OF BAYVILLE, NEW YORK.

BINDER.

Application filed September 23, 1927. Serial No. 221,427.

This invention relates to binders for letters and miscellaneous papers, and especially to a device whereby the papers are firmly but detachably secured to a cover or folder.

5 Various types of binders for the accumulation and filing of papers in an orderly manner are found in the trade including some with meritorious features. Many such devices are, however, relatively expensive and 10 others are unsatisfactory.

It is the object of the present invention to provide a binder having the advantages of simplicity of structure and ease of manipulation, which is nevertheless comparatively 15 inexpensive and adapted, therefore, for general use.

Another object of the invention is the provision of binders from which a file of papers may be removed readily without separating the papers.

Other objects and advantages of my invention will be understood as it is more fully described in the following specification with reference to the drawing, in which

25 Fig. 1 is a view in perspective of a binder embodying the invention;

Fig. 2 is an enlarged sectional view on the line 2—2 of Fig. 3;

30 Fig. 3 is a sectional view on the line 3—3 of Fig. 2;

Fig. 4 is a detail in perspective of the retainer; and

Fig. 5 is a detail in perspective of another form of retainer.

35 In carrying out the invention the cover or folder is made preferably of tough paper although more expensive materials such as cloth, imitation leather, or leather may be utilized. The cover is folded at the medial 40 line and at one side thereof a retainer of metal or other stiff material is riveted or otherwise secured to the cover. The retainer may consist, for example, of a metal plate having a free edge toward the fold of the cover and a channel formed therein to receive the base 45 of a paper fastener. The retainer is arranged so that the fastener can be slipped over the free edge and into the channel when the cover is flexed slightly therefrom. Normally the retainer engages the cover and holds the fastener in the channel.

The retainer may be made in various forms. For example, the channel may be stamped 55 therein to provide an inwardly projecting lip at the free edge of the retainer. Similarly a plurality of bosses may be struck from the

retainer adjacent the free edge. Preferably two spaced rows of such bosses are used to form a channel. Other suitable retaining means may be provided to hold the paper 60 fastener in the desired position.

A satisfactory paper fastener comprises a narrow flexible metal strip, the width of which corresponds, for example, to that of the channel in the retainer. The free ends of 65 the strip can be turned upwardly at the ends of the retainer to provide tongues which may pass through perforations in the papers to be bound. The tongues may also pass through openings in a keeper having, for example, 70 sliding locks to hold the ends of the tongues.

When the parts are assembled and the papers are secured in the fastener, the latter is firmly held in the retainer and cannot escape therefrom. To remove the bound papers 75 from the cover one of the tongues is released from the lock to permit the metal strip to be drawn away from the lowermost sheet. The strip can then be slipped over the free edge 80 of the retainer, the file of papers being thus released intact from the cover. The fastener 85 can be secured again to hold the papers in assembled relation and a new fastener can be inserted in the cover.

Referring to the drawing, 5 indicates the 85 cover of flexible material such as tough paper which is folded at 6. The retainer 7 comprises a metal plate riveted or otherwise secured to the cover parallel and in spaced relation to the fold. A channel 8 is stamped in 90 the retainer to provide a lip 9 which rests against the cover.

The fastener comprises a flexible metal strip 10 adapted to rest in the channel with its ends 11 forming tongues which pass 95 through perforations in the file of papers 12. A keeper 13 with openings 14 therein rests upon the top of the papers 12. The tongues 11 pass through the openings 14 and are secured by sliding locks 15.

When the keeper is in place and the tongues are locked thereby the metal strip 10 is firmly held in the channel and the file is thus secured to the cover. To remove the file, one of the sliding locks is moved to free the corresponding tongue 11. This permits the metal strip 10 to be drawn away from the lowermost paper of the file so that the strip can be slipped over the lip 9. The tongue 11 can then be locked again to secure the papers.

As indicated in Fig. 5, the retainer 16 may have a plurality of bosses 17 disposed in

spaced lines to provide a channel for the fastener. The bosses rest against the inner face of the cover and prevent the fastener from escaping. The fastener may be released in the manner hereinbefore described to permit removal of the file of papers.

It will be understood that the preferred forms of the invention are described and illustrated and that various changes may be made in the details thereof without sacrificing any of its advantages.

I claim:

1. In a binder for papers, a folded cover, a member secured to the cover with a free edge directed toward the fold thereof and means on said member adjacent the free edge adapted to retain paper-fastening means inserted under said free edge.
2. In a binder for papers, a folded cover, a member secured to the cover with a free edge directed toward the fold thereof, retaining means on said member adjacent the free edge, and a paper fastener comprising a narrow flexible strip held under said free edge by the retaining means.
3. In a binder for papers, a folded cover, a member secured to the cover with a free edge directed toward the fold thereof and means on said member adjacent the free edge and forming a channel adapted to retain paper-fastening means inserted under said free edge.
4. In a binder for papers, a folded cover, a member secured to the cover with a free edge directed toward the fold thereof, means on said member adjacent the free edge and forming a channel adapted to retain paper-fastening means inserted under said free edge, and a paper fastener comprising a narrow flexible strip in the channel.
5. In a binder for papers, a folded cover, a retainer secured to the cover adjacent the fold with a lip directed downwardly towards the cover and a fastener engaging the retainer and held therein by the lip, the fastener comprising a narrow flexible metal strip with

ends forming tongues and a keeper adapted to engage the tongues.

6. In a binder for papers, a folded cover, a retainer secured to the cover adjacent the fold with a channel and a lip directed downwardly towards the cover, and a fastener engaging the retainer and held therein by the lip, the fastener comprising a narrow flexible metal strip with ends forming tongues and a keeper adapted to engage the tongues.

7. In a binder for papers, a folded cover, a retainer secured to the cover adjacent the fold with a lip directed downwardly towards the cover, and a fastener engaging the retainer and held therein by the lip, the fastener comprising a narrow flexible metal strip with ends forming tongues and a keeper adapted to engage the tongues and sliding locks on the keeper.

8. In a binder for papers, a folded cover and a member secured to the cover adjacent the fold having a free edge on the side nearest the fold thereof, said free edge having a lip directed downwardly towards the cover 70 adapted to retain paper-fastening means inserted thereunder.

9. In a binder for papers, a folded cover and a member secured to the cover adjacent the fold having a free edge on the side of said member nearest the fold, said free edge having a lip directed downwardly towards the cover, and a paper fastener engaging said member and held therein by said lip.

10. In a binder for papers, a folded cover, a member secured to the cover adjacent the fold with a channel and a lip directed downwardly towards the cover, and a paper fastener engaging said member and held within said channel by the lip.

11. In a binder for papers, a folded cover and a member secured to the cover having a free edge on the side nearest the fold, said free edge being adapted to normally retain a paper fastener to the binder.

In testimony whereof I affix my signature.
FRED J. KLINE.
